UNITED STATES PATENT OFFICE

HAROLD C. KRETZ, OF ROCHESTER, NEW YORK

DESIGN FOR A COMBINATION FLOOR LAMP AND LOUD-SPEAKER

Application filed December 6, 1928. Serial No. 29,135. Term of patent 3½ years.

To all whom it may concern:

Be it known that I, HAROLD C. KRETZ, a citizen of the United States, residing at Rochester, in the county of Monroe and State of New York, have invented a new, original, and ornamental Design for Combination Floor Lamp and Loud-Speaker, of which the following is a specification, reference being had to the accompanying drawing, forming part thereof.

In the drawings:

I claim:

The ornamental design for a combination floor lamp and loud speaker as shown.

In testimony whereof I affix my signature.

HAROLD C. KRETZ.
